US0D1006870S

(12) **United States Design Patent** (10) **Patent No.:** **US D1,006,870 S**
(45) **Date of Patent:** **** Dec. 5, 2023**

(54) **TONER CARTRIDGE**

(71) Applicant: **TOSHIBA TEC KABUSHIKI KAISHA**, Tokyo (JP)

(72) Inventors: **Tokihiko Ise**, Shizuoka (JP); **Hiroki Sakurada**, Kanagawa (JP)

(73) Assignee: **TOSHIBA TEC KABUSHIKI KAISHA**, Tokyo (JP)

(**) Term: **15 Years**

(21) Appl. No.: **29/746,786**

(22) Filed: **Aug. 17, 2020**

(30) **Foreign Application Priority Data**

Feb. 28, 2020 (JP) ..... 2020-003800 D

(51) **LOC (14) Cl.** **16-03**

(57) **CLAIM**

We claim the ornamental design for a toner cartridge, as shown and described.

DESCRIPTION

FIG. 1 is a front perspective view of a toner cartridge; FIG. 2 is a right side view of the toner cartridge of FIG. 1; FIG. 3 is a left side view of the toner cartridge of FIG. 1; FIG. 4 is a top view of the toner cartridge of FIG. 1; FIG. 5 is a bottom view of the toner cartridge of FIG. 1; FIG. 6 is a front view of the toner cartridge of FIG. 1; FIG. 7 is a rear view of the toner cartridge of FIG. 1; FIG. 8 is a detail view of the portion labeled 10 in FIG. 1, as seen from a rotated perspective view; FIG. 9 is a detail view of the portion labeled 10 in FIG. 1, as seen from a top view; and, FIG. 10 is a detail view of the portion labeled 10 in FIG. 1. The ornamental design which is claimed is shown in solid lines in the drawings. The broken lines shown in the drawings represent portions of the toner cartridge that form no part of the claimed design. The broken lines indicating the detail views labeled 10 in FIG. 1 represent the bounds of the detail views and form no part of the claim.

1 Claim, 5 Drawing Sheets
